SCARF HOLDER

Nat Levy, New York, N. Y.

Application June 11, 1936, Serial No. 84,645

2 Claims. (Cl. 24—82)

This invention relates to garment clips or fasteners, and particularly to that type which is adapted to hold a scarf in place about the neck of the wearer.

5 My invention contemplates the provision of a simple and efficient holder designed to hingedly carry a suitable ornament in such a manner that the ornament may be utilized to hold the ends of a scarf against flying about, and further designed to be readily attached to and detached from any part of the outer garment of the wearer so as to arrange the scarf in any desired position.

10 My invention further contemplates the provision of a scarf holder adapted for ready attachment to and removal from any desired part of a dress, coat or other outer garment, and carrying a pair of opposed ornaments in such positions that the ornaments may be used to hold the end portions of a scarf or the like about the neck of the wearer.

15 My invention further contemplates the provision of a simple and comparatively inexpensive holder having an ornamental function, combined with a scarf-holding function, and adapted to be readily attached to and detached from a convenient point of a garment, and after attachment being adapted for easy manipulation to hold the scarf in place.

20 The various objects of the invention will be clear from the description which follows and from the drawing, in which,

25 Fig. 1 is a perspective view of my improved scarf holder as it appears attached to a garment and in operation.

Fig. 2 is a top plan view of the same.

30 Fig. 3 is a fragmentary perspective view of an end part of the same.

35 Fig. 4 is a similar view of one end of the frame portion of the holder, showing a modified form thereof in which the frame is made of a single piece of sheet material.

40 Fig. 5 is a vertical section of the same taken on the line 5—5 of Fig. 4.

45 Fig. 6 is a fragmentary horizontal section of the other end part of the frame portion of the holder, showing particularly the integral lugs for holding the pointed end of the pin in place.

50 In the practical embodiment of my invention, which I have shown by way of example, my new holder consists of a frame member designated generally by the numeral 10, a hinged pointed pin 11 carried at the back of the frame member, and a pair of spaced combined ornament and scarf

holding members 12 and 13 hinged to the front of the frame member 10.

5 As shown particularly in Figs. 2 and 3, the frame member 10 comprises the elongated and comparatively narrow and thin body portion 14, made preferably of suitable bendable metal such as the white metal composition commonly used in clips, brooches and the like. Said portion 14 is preferably curved laterally to conform to the shape of a body portion of the wearer, such as 10 the shoulder, breast, or any other point at which the wearer may desire to secure the holder.

10 The ornaments 12 and 13 are preferably hingedly mounted at the end parts of the member 10 and the adjacent inner ends thereof are preferably in longitudinal spaced relation. Each of said ornaments may be made of any suitable material, preferably metal, and may be set with rhinestones or other ornamental genuine or imitation precious stones and/or may be otherwise 20 suitably ornamented. It will be understood that said ornaments may take a great variety of different forms and sizes and may if desired be such as can be purchased in the open market, but in any case, I prefer to so mount said ornaments 25 that the respective end portions 15 and 16 thereof, may contact, when permitted to do so, with the outer face 17 of the frame member 10, and to engage the scarf ends inserted therebetween and to hold said ends against disarrangement 30 or flying about.

35 Preferably, each of the ornaments is mounted on an ornament holding member as 18, of suitable shape, preferably convex outwardly, and preferably of less length than the ornament and of 35 approximately the same width and thickness as that of the frame portion 14. The ornament 12 may be secured to the ornament holder 18 in any suitable manner, as by solder or other suitable fastening means.

40 The ornament carrying member 18 is pivotally mounted on the end part of the frame portion 14, as by means of a pair of lugs 19 and 20 extending from said member. Said lugs may form the depending parts of a U-shaped member, which includes the cross bar 21 joining said lugs and secured to the inner face or to the end part of the member 18. Of if desired, said lugs 19 and 20 may be formed integrally with and bent from the end part of said member 18. The 45 lugs 19 and 20 in any case, are perforated for the reception of the hinge pin 22 which passes through said lugs and also through the upstanding perforated spaced lugs 23, 24 of a suitable bracket 25. Said bracket is soldered or other- 50 55

wise suitably secured to the outer face 17 of the member 14.

For urging the end part 15 of the ornament 12 into contact with the outer face 17, a spring such as, for example, the coil spring 26, is coiled about the pin 22 and is arranged between the lugs 19 and 20. One end as 27 of the spring may be bent around and anchored to the lugs 19 and/or 23, while the other end 28 of the spring may be similarly bent around and anchored to the lugs 20 and/or 24.

Since the ornament 13 is mounted on a holding member similarly hinged to the frame holding part 14 by means identical with that just described, the above description in connection with the ornament 12 applies equally well to the holding means for the ornament 13. It will be understood that if desired, one of the ornaments and the holding means thereof may be omitted, and a single ornament and holder of the proper size used instead of a pair of such ornaments.

As has been indicated, the means for securing the holder to an article of apparel comprises the pin 11 and suitable means for hinging the pin to the rear face of the frame member 14. Said hinging means may take any convenient form, but as shown, the bracket 30 is provided with a base 31 preferably soldered to the rear face of the member 14, and is also provided with a pair of spaced outstanding perforated lugs 31'. The pin 32 passes through said lugs and through a suitable eye or loop 33 at the unpointed end of the pin 11, whereby said pin is hingedly supported by the bracket for swinging movement toward and from the frame member.

The pointed end 34 of the pin is detachably held in place in a conventional manner as by means of the hook shaped bracket 35, preferably soldered to the portion 14 and provided with a rotatable catch 36 having a suitable opening or slot therein to permit the end 34 of the pin to be inserted transversely therethrough and into the bracket, and being rotatable to close the open side of the bracket and to fasten the pin in position after the pin has been passed through the article of apparel to attach the holder in place.

In that form of my invention shown in Figs. 4, 5, and 6, the frame member of the holder is made of a single piece of sheet material, the various holding lugs being integrally bent from the material thereof. Referring now to Fig. 4, the main body portion 40 of the frame member is similar to the portion 14, but at its ends is provided with the integral lugs 41 and 42 bent at right angles to and outstanding forwardly from the body portion 40. The lugs 41 and 42 are perforated as at 43, 44 similarly to the lugs 23 and 24, and receive a similar hinge pin on which are mounted the lugs projecting from the ornament holder 18.

For the separate bracket 30, may be substituted the pair of spaced parallel integral lugs 45, 46 (Figs. 4 and 5) bent from the material of the body portion 40. Said lugs are separated from said material by means of suitably shaped cuts 47, 48. The lugs 45 and 46 are perforated for the reception of the hinge pin 49 about which the loop 50, at one end of the attaching pin 11, is bent. It will be understood that said pin 11 is rotatable about the hinge pin 49 into and out of its operative position.

Similarly near the other end of the body portion 40, a pair of lugs as 51, 52 are struck in-

wardly from the material of the body portion, said lugs being provided with a side opening or slot 53 for the entrance of the pointed end 34 of the pin 11. A suitable rotatable catch as 54 is arranged between lugs 51 and 52 to detachably hold the pointed end 34 in place.

In operation, the scarf holder is preferably first attached at the desired point of the garment by removing the pointed end 34 of the pin from the bracket 35 or from the lugs 51, 52, opening the pin about its hinge and then passing the pin through the article of apparel after which the pointed end is re-engaged with its catch, thereby securing the holder to the garment. The hands of the wearer are now free to open the ornament to the position shown in dotted lines in Fig. 2 so that the end portions of the scarf may be arranged behind the ornament and in front of and against the frame member. The ornament being then released, the spring 26 serves to close the ornament against the scarf which enters the space 60 between the ornament and the portion 14. Said spring urges the portion 15 of the ornament toward the frame portion 14 and prevents the scarf from leaving the space 60. The ornament 13 may be similarly manipulated to hold the other end part of the scarf in the space 61.

It will be understood that since my improved scarf holder may be attached to any desired point of the upper part of a garment, it becomes possible to arrange a scarf about the neck of a wearer in a variety of different ways to suit the taste and desires of the wearer. It will also be seen that my new holder may be quickly and easily attached in place and provides an efficient ornamental securing means for a scarf, and because of its simplicity may be manufactured at comparatively low cost.

While I have shown and described certain specific embodiments of my invention, I do not intend to be understood as limiting myself thereto, but desire to claim my invention as broadly as may be permitted by the state of the prior art and the terms of the appended claims.

I claim:

1. In a scarf holder, a forwardly convex elongated frame member of uniform width, a pair of transversely spaced, perforated lugs extending forwardly from each end of said frame member, a pair of forwardly convex ornament holding members, a pair of transversely spaced perforated lugs extending rearwardly from an end of each of the ornament holding members, said last mentioned pair of lugs of each of the holding members being arranged between the respective first mentioned pairs of lugs, a hinge pin passing through said pairs of lugs, a coil spring wound about each of the hinge pins and urging the holding members toward the frame, an ornament member secured to the front face of each of the holding members and projecting beyond the free end of the holding member and of sufficient length to press against the frame member in the operative scarf holding positions thereof, an attaching pin hingedly mounted on the rear face of the frame member, and means on said rear face for detachably engaging the pin.

2. In a scarf holder, an elongated frame member, a pair of transversely spaced, perforated lugs extending from each end of said frame member, a pair of ornament holding members, a pair of transversely spaced perforated lugs ex-

tending rearwardly from an end of each of the ornament holding members, a hinge pin passing through said pairs of lugs, a coil spring wound about each of the hinge pins and urging the holding members toward the frame, an ornament member secured to each of the holding members and projecting beyond the free end

of the holding member and of sufficient length to press against the frame member in the operative scarf holding positions thereof, an attaching pin hingedly mounted on the rear face of the frame member, and means on said rear face for detachably engaging the pin.

NAT LEVY.
